UNITED STATES PATENT OFFICE.

GEORGE E. SAVAGE, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A BEVERAGE-PERCOLATOR.

No. 38,071.

Specification for Design.

Patented June 12, 1906.

Application filed April 30, 1906. Serial No. 314,609. Term of patent 14 years.

To all whom it may concern:

Be it known that I, GEORGE E. SAVAGE, a citizen of the United States, residing at Meriden, State of Connecticut, (post-office address the same,) have invented a new, original, and ornamental Design for Beverage-Percolators, of which the following is a specification, reference being had to the accompanying drawing, forming part thereof.

The figure is a side elevation of a beverage-percolator, showing my new design.

I claim—

The ornamental design for a beverage-percolator, as shown.

GEORGE E. SAVAGE.
